DISPLAY DEVICE

David Davis, New York, N. Y.

Application June 23, 1942, Serial No. 448,115

5 Claims. (Cl. 206—75)

This invention relates generally to containers or boxes of the type which are customarily furnished with watches, articles of jewelry and the like, in which such articles may be deposited when not in use and is more particularly directed to a container or box formed to function as a protective receptacle for a wrist watch and its attaching band or bracelet, when the watch is not being worn, which is also adapted for conversion to serve as a rack for displaying the watch for merchandising or other purposes.

The principal object of this invention is to eliminate the necessity for separate display racks or stands in merchandising watches and other items of the kind, in the sale of which protective receptacles or so-called cases are customarily furnished, while at the same time providing for the display or exhibition of such items in an attractive and sales-promoting manner.

More specifically, it is an important object of this invention to provide a container or protective case for a wrist watch and its attaching band, in which the watch and its band may be deposited when not in use, which is readily convertible into a display rack or stand for merchandising or other exhibition of the watch.

It is also an object of this invention to provide a combination watch case or protective enclosure and display stand, as aforesaid, which may be economically produced from a single blank of material to form the cooperating base, side walls and top of the case, these components being capable of association in another relationship in the alternative functioning of the case for display purposes, the case embodying a receptacle for a watch and wrist band, which is shiftable from a position within the case to an external position, when conversion of the case for display purposes is effected.

Other objects and advantages flowing from the practicing of my invention will become apparent as the description proceeds.

For the purposes of this disclosure I have elected to show a preferred embodiment of my invention in the accompanying drawing, which is designed for protectively enclosing and displaying a wrist watch and the attaching bracelet associated therewith. However, my invention may take other forms and be used for enclosing and displaying other articles, as pieces of jewelry and the like, as will be obvious from the detailed description thereof.

In the drawing:

Figure 1 is a view in perspective of my combi-

nation case or container and display rack or stand.

Figure 2 is a cross-sectional view on the line 2—2 of Figure 1.

Figure 3 is a top plan view of the container in open or collapsed condition.

Figure 4 is a view in perspective of the combination container and display rack, showing how it functions in the latter use, and

Figure 5 is a transverse section on the line 5—5 of Figure 4.

Referring now to the drawing in detail, in which like characters of reference indicate similar parts in the several views, the case or container, which, as shown, is designed for the reception of a wrist watch and its wrist embracing band, is of an elongated rectangular shape to receive the watch positioned centrally of the ends thereof, with the wrist band disposed in flattened condition on either side thereof.

The case, which may be made of any suitable material, as fibre board or the like, covered in simulation of leather or other material and appropriately lined, is of a unitary construction, embodying a base section and laterally projecting flaps 8 and 9 foldable upwardly to form the sides of the case and inwardly to overlie said base section, the length of the two flaps being co-extensive with that of the base section.

Superimposed upon the base section is an inner base member 10 of a relatively rigid construction which is formed for the reception of a wrist watch and attached wrist band, collectively indicated at 11, with the watch located centrally of the ends of said member, the sections of the wrist band being arranged on either side thereof, in open or a substantially flattened condition.

To provide for the reception of the watch and wrist band, as just described, the inner base member 10 embodies an elongated recess of a width approximately the same as that of the standard wrist band, the central portion of the recess being enlarged to form a locating seat for the watch. In the present showing, the watch and wrist band receiving recess in the inner base member, is formed by the parallel ribs 13 and 14 superimposed upon said member and extending from end to end thereof along its sides, the opposed inner surfaces of said ribs, intermediate their respective ends, being cut back in oppositely disposed curved lines, to provide the aforesaid watch locating seat indicated at 12, the parallel surfaces of said ribs defining the pocket 11 for the wrist band 11 of the watch.

Pieces of material, as cardboard, indicated at 16 and 17, superimposed upon the ribs 13 and 14 and spanning the pocket 11 are folded down upon the outside surfaces and ends of said ribs and cemented thereto, to form end walls for said inner base member, the ends of the wrist band being insertable beneath these pieces 16 and 17, when the disconnected band sections are arranged within in the pocket 11, on either side of the watch located on the seat 12, as shown in Figure 3.

To protectively enclose the watch, the oppositely projecting flaps 8 and 9 are folded thereover to form the sides of the case, along the hinge lines 8a and 9a and again along the hinge-forming lines 8b and 9b, the latter folds disposing the free ends of the respective flaps parallel to said base section 7, with the free end 8c of the flap 8 overlapping the free wider portion of the flap 9, the interengagement of the cooperating snap fastener elements 18 and 19, completing the enclosure, as shown in Figure 1. As will be observed, the spacing between the parallel hinge lines 8a and 8b is greater than that between the hinge line 9a and 9b, the opposite walls 8d and 9d of the closed case, as defined thereby, being unequal in height to afford sufficient clearance between the face of a watch superimposed upon the seat 12 and the undersurface of the closure formed by the engaged free ends of the flaps 8 and 9 and to permit of the flap sections between said hinge lines to function in the alternative use of said case as a display rack, as hereinafter described.

When it is desired to employ the case or container in the display or exhibition of the watch and wrist embracing band, the disconnected free ends 8c and 9c of the flaps 8 and 9 are reversed upon their respective hinge lines 8a and 9a, to locate them beneath the base section 7, with the free end 8c of the flap 8 superimposed upon the inner surface of the free wider end 9c of the flap 9, the two flap ends being then connected in their inverted positions, by the opposed snap fastener elements 18 and 19. The opposite directional reversal of the positions of the respective flaps 8 and 9, relatively to the inner surface of the base section 7 and the inner base member 10 carried thereon, shifts said base section to topmost position and exposes the inner base member 10 for unobstructed observation, the latter member, with the base section, being disposed in a plane inclined from the vertical, by virtue of the differential in the height of the wall portions of the flaps, as defined by the hinge lines 8a, 8b and 9a, 9b, as heretofore pointed out, it being apparent that the mated free ends 8c and 9c of the flaps 8 and 9 are adapted to function as the base or support of the display rack that is provided in the reversal of said flaps in the manner just described.

By disposing the inner base member 10 at an angle, it will be obvious that the watch and wrist band arranged thereon, will be adequately supported against dislodgment by the cooperating seat and pocket, at an angle which will be most effective in their display or exhibition, the general decorative appeal of the ensemble being enhanced by a plush covering with which the inner base member 10 and the end pieces 16 and 17 may be faced and the rolled frontal edge effect that obtains in the reversal of the wall-forming portion 9d of the flap 9.

While I have described my invention with reference to a combination case and display rack designed for a wrist watch and wrist band, it will be obvious that my invention may be employed to equal advantage in the use and merchandising

of other articles of utility and adornment, such variations in dimensions of the container and in the configuration of the inner base member 10, as may be necessary, coming within the spirit and scope of my invention, as defined by the appended claims.

I claim:

1. A case formed of a single blank of material folded along four lines to provide a base section, side walls and a closure adapted to overlie the base, the closure being formed by overlapped portions of the blank, fastening means for connecting the overlapped portions in closure-forming position and an inner base member fixed to the inner surface of said base section and formed for the reception of the article to be deposited in said case, said side and closure-forming portions of said blank being reversible relatively to said base section along the lines of said folds to dispose said closure-forming portions beneath said base section for interconnection by said fastening means, said base being shifted for support by said side walls, said inner base member being shifted thereby to a topmost exposed position, for the display of an article superimposed thereon.
2. A case formed of a single blank of material, folded along parallel longitudinal lines, to define a base section, side walls and a closure adapted to overlie the base section, the closure being formed by overlapped portions of the blank, fastening means carried by said overlapped portions for securing them in closure-forming position and an inner base member fixed to the inner surface of said base section and shaped for the reception of an article to be deposited in said case, said side and closure-forming portions of said blank being reversible relatively to said base section along the lines of said folds to dispose said closure-forming portions beneath said base section for interconnection by said fastening means and to dispose said side walls to support said base section, whereby said inner base member is maintained in an exposed topmost position, for the display of an article superimposed thereon.
3. A combination case and display rack, comprising a single blank of material, folded along parallel longitudinal lines, to define an elongated base section, side walls of different heights and a closure adapted to overlie said base section, the closure being formed by overlapping the free ends of the blank, fastening means carried by the overlapping free ends of the blank for securing them in closure-forming position and an inner base member fixed to the inner surface of said base section and conformed for the reception of an article to be deposited in said case, said side and closure-forming portions of said blank being adapted to be folded in reverse directions relatively to said base section, to dispose said closure-forming portions beneath said base section for interconnection by said fastening means, to support said inner base member fixed to said base section in an exposed topmost position, for the display of an article superimposed thereon, the wall portions defined by adjacent fold lines imparting a downward inclination of said exposed inner base member from one of said wall portions to the other thereof.
4. A combination case and display rack for protectively enclosing a wrist watch and associated wrist band, supporting such watch and wrist band in an exposed position for exhibition, comprising an elongated base section, side-forming members hinged thereto and sections hinged to

said side-forming members adapted to be disposed in overlapping engagement substantially parallel to said base section to form a closure for the case, fastening means carried by said overlapping sections to connect them in closure-forming position, and an inner base member carried by said base section, said inner base member embodying a seat for said watch and a depression on either side thereof for the reception of the wrist band thereof, said side-forming members being reversible on their hinge lines relatively to the base section to dispose said side-forming portions below said base section, said closure-forming sections being reversible relatively to the side-forming portions to which they are respectively hinged for overlapping engagement beneath said base section, whereby said engaged closure-forming sections will function to support said base section to dispose said inner base member in topmost position to completely expose said member for the display of a watch and wrist band in engagement with said seat and depression respectively.

5. A combination case and display rack for protectively enclosing a wrist watch and associated wrist band or supporting such watch and wrist band in an exposed position for exhibition, comprising an elongated base section, side-forming portions hinged thereto, said side-forming portions being of different heights, and sections

20 hinged to said side-forming portions adapted to be superimposed one upon the other in spaced relation to said base section to form a closure for said case, fastening means carried by said closure-forming sections to connect them in closure-forming position, and an inner base member carried by said base section embodying a centrally located watch seat and a groove extending from either side thereof toward the respective ends of said inner base member for the reception of the wrist band of a watch disposed on said seat, said side-forming portions being adapted to be reversed on their hinge lines to assume a position below said base section, said closure-forming sections being oppositely reversible along their hinge connections with said side portions to dispose said closure-forming sections beneath said base section in overlapped engagement for the interengagement of said fastening means, whereby said closure-forming sections will function as the supporting base of the display rack, said inner base member being supported therefrom in a topmost exposed position for the exhibition of a watch and wrist band associated therewith, said side-forming portions cooperating with said closure-forming sections to support said inner base member in a transversely inclined plane.
